UNITED STATES PATENT OFFICE

HARRY R. PRIEST, OF LOUDONVILLE, OHIO

SHAVING OUTFIT

Application filed July 12, 1930. Serial No. 467,605.

This invention relates to shaving outfits and has for an object to provide an attractive compact fountain shaving mug adapted to carry all the necessary articles for shaving, the entire outfit occupying but minimum space so as to be conveniently carried in a traveling bag.

A further object of the invention is to provide a fountain shaving mug having a two-compartment screw base, one of the compartments forming the shaving cream magazine and the other forming a storage space for the safety razor and other small articles, both compartments having a common outer cylindrical wall which is preferably interiorly threaded throughout to screw onto the shaving mug and into which the safety razor receptacle is screwed.

A further object of the invention is to provide a fountain shaving mug having a hump in the base connected to the magazine by a duct disposed axially in the hump, the hump serving to put the cream from the duct well up into the center of the bristles of the brush so that an effective lather may be quickly produced with a minimum amount of cream.

A still further object of the invention is to provide the fountain shaving mug with a removable cover which is provided on the flat face with a mirror of sufficient size to be used as a shaving mirror, the cover having a marginal flange provided with a ventilating orifice so that a knock-down shaving brush as well as other toilet articles which may be stored within the shaving mug will be adequately ventilated and thus maintained in a sanitary condition.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a perspective view of the foun-

tain shaving mug embodying my improvements,

Fig. 2 is a longitudinal sectional view through the shaving mug showing the arrangement of the toilet articles stored within the mug and base thereof, and

Fig. 3 is a cross sectional view taken on the line 3—3 of Fig. 2.

Referring now to the drawings in which like characters of reference designate similar parts in the various views, 10 designates a fountain shaving mug having the bottom thickened and reversely bowed to provide a hump 11, the upper surface of which is substantially semi-spherical in contour and extends nearly to the cylindrical side wall of the mug.

The bottom of the mug between the side wall and hump is downwardly curved, as shown at 12, to provide a concave annular surface which coats with the side wall and the hump in receiving toilet articles, such as a face powder container 13, a face lotion bottle 14, and a knock-down shaving brush comprising a handle 15 and a brush component 16, as well as other shaving necessities, such as chamois skin, etc.

The hump is provided axially with a duct 17 through which shaving cream from the magazine may enter the mug. The duct is closed at the inner end by a removable stopper 18. The purpose of the hump is to spread the bristles 16 of the brush apart from the center outwardly and thus put the cream from the duct well up into the bristles so that an effective lather may be quickly produced.

A two-compartment cylindrical base 19 is screwed onto the mug at the bottom thereof. A transverse partition 20 is disposed substantially midway of the cylindrical wall of the base and divides the base into an upper magazine compartment adapted to be filled with a supply of shaving cream sufficient to last several months, and a lower compartment adapted to receive a container for the shaving tools. The inner face of the magazine compartment is threaded as shown at 21 to engage similar threads 22 on the wall of the mug at the bottom thereof. A quarter turn of the magazine is sufficient to eject a small

quantity of shaving cream through the duct 17 into the shaving mug after removal of the stopper, sufficient for a single shave, whereupon the magazine may be reversely turned 5 to prevent further escape of the shaving cream into the mug and thus economy will be promoted.

Preferably, the shaving tool container comprises a base 23 having a marginal flange 24 10 which engages the wall 19 of the two-compartment base and forms a grip to permit unscrewing of the container as well as forming a stop to limit advance of the container into the lower compartment of the mug base 19. 15 The container is provided with an unstanding flange 25 which is threaded exteriorly near the upper end, as shown at 26, to engage similar screw threads 27 cut in the inner face of the cylindrical wall 19 of the mug base. 20 The container is of sufficient height to hold a safety razor case as well as other shaving tools, such as tweezers, caustic stick, etc.

The shaving mug 10 is closed by means of a cover 28, the same having a marginal flange 25 29 adapted to seat upon an annular ring 30 formed integral or otherwise secured to the wall of the mug. The flange is cut away for a portion of its lengths to provide an elongated ventilating opening 30 which thoroughly 35 ventilates the interior of the mug when the cover is closed and maintains the contents of the mug, such as the toilet articles above enumerated, in a sanitary condition.

A mirror 31 is secured preferably to the 35 inner flat surface of the cover in any preferred manner and is of sufficient diameter to extend nearly to the circumferential flange of the cover and is thus of sufficient size to be used as a shaving mirror when desired.

If desired, the screw thread connection between the shaving mug and cream magazine 40 may be dispensed with and a sliding connection substituted therefor, and the same is true for the screw thread connection between the safety razor container and the base.

While a hump is illustrated in the drawing and described in the specification, it is not essential to the fountain feature of the outfit, since it is conceivable that the bottom 50 of the shaving mug may be even formed concave throughout instead of convexed to provide a hump, and where the hump is dispensed with and a concavity utilized in lieu thereof, obviously a greater storage space for 55 toilet articles will be formed in the interior of the mug.

While the cover is shown equipped with a mirror on the inner surface thereof, it is not essential that the mirror be so placed, 60 since the mirror might conceivably be placed on the outer surface of the cover, which in some instances would lend to the attractiveness of the outfit without departing from the spirit of the invention.

It will be observed that the traveler's outfit

above described is extremely compact and attractive in appearance. Furthermore, all the necessities for shaving are carried thus in a single unitary structure. It will be also pointed out that the shaving outfit is composed of a few strong and durable parts which will be inexpensive to manufacture and will not easily get out of order under severe conditions of service.

Having thus described the invention, I 75 claim:

1. A shaving outfit comprising a mug having an axial duct in the bottom, a cover for the mug, and a base for the mug comprising an upper and lower compartment separated by a transverse partition, the inner face of the base being threaded above and below the partition, the upper threads screwing onto the base of the mug, said upper compartment comprising a magazine for shaving cream, 80 and a container for shaving tools having a marginal flange threaded to engage the threads of the base disposed below said partition.

2. A shaving outfit comprising a fountain 90 shaving mug having a centrally disposed hump in the bottom thereof provided with an axial duct, said hump being substantially semi-spherical in contour, the bottom of the mug being concave between the hump of the 95 side wall and coacting with the side wall and the hump in receiving toilet articles, a cover for the mug having a lateral ventilating orifice, a mirror on the inner surface of the cover, and a shaving cream magazine removably 100 secured to the bottom of the wall of the mug.

3. A shaving outfit comprising a mug, a removable cover for the mug, there being a duct disposed in the bottom of the mug, a cylindrical base for the mug having a screw 105 thread connection with the bottom of the mug, a transverse partition in the base forming a shaving cream magazine above the partition and forming a compartment below the partition, and a shaving outfit container 110 threaded into said base below the partition and having a marginal flange engaging the bottom edge of the wall of said base and performing the dual function of a grip to unscrew the container and a stop to limit advance of the container into said base.

4. A shaving outfit comprising a mug having an exterior flange near the top thereof, a cover having a marginal flange seating on said exterior flange and provided with a ventilating orifice, a mirror on the flat surface of said cover, a cylindrical base for the mug having a transverse partition, the inner face of the base being threaded above and below said partition, the outer wall of the mug being threaded at the bottom to engage the threads of the base above said partition, said base constituting a shaving cream magazine above said partition, and a container having a marginal flange provided with exterior 125

screw threads engaging the screw threads of the base below said partition, said container providing a compartment for the storage of tools below said partition.

5 5. A shaving outfit comprising a shaving mug, a two-compartment base for the shaving mug, the upper compartment forming a shaving cream magazine, a removable container removably secured to the lower compartment,
10 said base and container being movable as a unit longitudinally of the mug, the base of the mug being humped centrally to spread the bristles of the shaving brush when making lather and being provided with an axial
15 duct opening therethrough into said magazine, and a removable stopper closing the inner end of said duct.

6. A shaving outfit comprising a fountain shaving mug having a bottom provided with
20 an axial duct, a cylindrical base having a centrally located transverse partition dividing the base into an upper and lower compartment, a container removably disposed in the lower compartment, the upper com-
25 partment forming a shaving cream magazine, said bottom of the mug forming the upper wall of the magazine, and a flanged cover for the shaving mug having the flange thereof cut away for a considerable portion
30 of its length to provide an elongated venti-
lating opening for the interior of the mug.

In testimony whereof I affix my signature.
